DIVIDER RESISTANCE

Paul M. Ross, Barberton, Ohio, assignor to The Ohio Brass Company, Mansfield, Ohio, a corporation of New Jersey

Application April 23, 1938, Serial No. 203,857

6 Claims. (Cl. 201—63)

This invention relates to a potentiometer or divider resistance and particularly to a resistance for use in connection with apparatus for recording the wave forms of high potential surges.

5 One object of the invention is to provide a divider resistance in which the wave form of the voltage will be substantially the same at the low potential end of the resistance as at the high potential end; the resistance having means associated therewith for avoiding the effect of capacitance between portions of the resistance and earth.

A further object of the invention is to provide a potentiometer or divider resistance which shall be of improved construction and operation.

Other objects and advantages will appear from the following description. The invention is exemplified by the combination and arrangement of parts shown in the accompanying drawing and 20 described in the following specification, and it is more particularly pointed out in the appended claims.

In the drawing:

Fig. 1 is a diagrammatic representation of a 25 divider resistance made according to the present invention and applied to the oscillograph circuit of a high potential impulse generator.

Fig. 2 is a fragmentary sectional view of one 30 unit of a divider resistance made according to the present invention together with a portion of a connected unit, the figure also showing means for connecting the two units.

Fig. 3 is an elevation of the circuit contacts connecting resistance elements of adjacent units, the view being taken at right angles to Fig. 2.

Fig. 4 is an end view of one of the resistance units.

In the investigation of the characteristics of many high potential electrical devices, it is desirable to make a record of the wave form of high potential surges applied to these devices. The surges are usually produced by some form of surge generator and apply in the manner described in Patent No. 2,077,773 granted April 20, 40 1937, to Harold L. Rorden and myself, and assigned to The Ohio Brass Company of Mansfield, Ohio. I have discovered that in many oscillograph records, there is an appreciable variation between the wave form of the voltage impressed 45 on the test piece and the wave form recorded by the oscillograph due to the capacitance currents to ground from the various portions of the divider resistance interposed between the high potential electrode and the oscillograph.

50 In Fig. 1 of the drawing, the numeral 10 des-

ignates the high potential electrode of a surge generator, which in operation is connected to one terminal of the piece of electrical apparatus to be subjected to surge voltages. The electrode 10 is also connected to a non-inductive divider resistance 11, the other end of which is connected through a cable 12 and a second non-inductive resistance 13 to ground. Spaced points on the resistance 13 are connected to the opposite surge deflector plates 14 and 15 respectively, of the oscillograph to impart a motion to the cathode ray of the oscillograph, corresponding to the wave form of the voltage impressed on the two plates. The operation of the impulse generator and the oscillograph are more fully described in the patent referred to above.

5 I have discovered that the voltage at the point 16 which is recorded by the oscillograph may vary slightly in wave form from the voltage at the point 13, and that this variation is due to 20 the capacitance to ground of the various portions of the resistance 11. By Ohm's law, the voltage between any two points in a circuit of pure resistance is equal to the current flowing in the circuit times the resistance between the two 25 points and this is independent of any time element, but this law, in its simple form, does not apply to circuits containing capacitance. The equation of the various capacitance circuits between the various points along the resistance 11 30 and ground, contains a time factor, and a part of the current flowing between the electrode 10 and ground passes through these various capacitance circuits. The amount of current at any instance, passing through these shunt circuits 35 will vary as a factor of the time elapsed after the voltage is impressed on the electrode. Since the current passing through the resistance conductor 11 at the point 16 is in shunt with the current in these various capacitance circuits, the current 40 at this point will depend upon a time factor due to the time factor of the capacitor shunt circuits. The voltage at the point 16 will, therefore, depend upon a time factor and will not be a constant function of the voltage at the point 13; 45 hence, the wave form recorded by the oscillograph will not be a true representation of the wave form on the electrode 10, due to the error introduced by the time factor in the capacitance circuits between the various portions of the resistance 11 and ground.

50 To overcome this difficulty, I have surrounded the non-inductive resistance 11 with a second non-inductive resistance 17 connected to ground through a resistance 18 which is equal to 55

the total resistance between the point 16 and ground. The resistance in the winding 17 is distributed along the resistance of the winding 11 proportionally to the distribution of the resistance in the winding 11, so that the drop of potential along the winding 17 will be the same as the drop along the winding 11 and the voltage at any point along the winding 17 will be the same as the voltage at the adjacent point along the winding 11. It will be seen that the winding 17 forms a capacitance coupling with the winding 11, but that the opposite points in this coupling are always of equal potential, so that there is no tendency for capacitance current to flow between the two windings. This arrangement completely removes any capacitance current between the winding 11 and ground, so that with the new arrangement, the pure non-inductive resistance 11 constitutes the only circuit between the points 19 and 16, and consequently, the voltage at the point 16 at any instant will be a direct factor of the voltage at the point 19, and the wave form recorded by the oscillograph will be an exact reproduction of the voltage wave form impressed on the electrode 10. It is true that the capacitance between the winding 17 and ground will have a slight effect upon the voltage at the different points along the winding 17, but this variation of the voltage of winding 17 from the voltage at the adjacent points of winding 16 will be so slight that the capacitance current between the two windings caused thereby can be scarcely detected, and consequently, the effect upon the oscillograph record will be negligible. This error can be still further reduced if found desirable by adding other concentric resistance paths, each added resistance reducing the error many fold. In practice, however, one shielding resistance will usually be sufficient.

40 The divider resistance or potentiometer for a surge generator is usually made up in several units connected together in series and one form of resistance element embodying the present invention is illustrated in Figs. 2, 3, and 4. In the embodiment shown there, each unit is provided with a housing comprising a tube or shell 19 made of suitable rigid dielectric material. Metal caps 20 are secured to the opposite ends of the tube 19 by cap screws 21 engaging collars 22 cemented to the tube 19. A second dielectric tube 23 is disposed inside the tube 19 and held in place by shoulders 24 on the inner faces of the metal caps 20. Within the tube 23 there is a plurality of cards or plates of insulating material 25 each non-inductantly wound with a resistance wire 26, the cards and wires being connected by metal straps 27. The ends of the wires 26 of the endmost plates 25 are each connected to a contact member 28. The contact members 28 extend through insulating bushings 29 in the caps 20 of adjacent units, and the end of the contact member at one end of each of the units is provided with a spring clip 30 which engages a contact clip 31 on the adjacent unit as shown more clearly in Figs. 2 and 3. One end of each unit is provided with eyes 32 which engage hooks 33 on the adjacent end of the adjacent unit. It will be seen that the various resistance units can be readily connected and disconnected to form a series of units of any desired length, and that when they are connected, the windings 26 will be connected in series by the contact clips 30 and 31 to form the divider resistance.

75 Each of the dielectric tubes 23 is non-induc-

tantly wound by a resistance 34, the ends of the windings 34 being connected by conductor strips 35 to the caps 20 at the ends of the tubes 19. It will be seen that the winding 34 of each unit will have its opposite ends connected through the eyes 32 and hooks 33 with the adjacent ends of the corresponding windings in the next adjacent units in the string. The windings 34 are thus all connected in series to form the winding 17 of Fig. 1. To form a capacitance shield for the portion of the inner non-inductive circuit formed by the electrodes 28 and contact clips 30 and 31, conducting sleeve 36 connects the end caps of adjacent units and surrounds the contacts between these units. This sleeve 36 may be of spring material, such as phosphor bronze, so as to make good electrical connection with the adjacent end caps and assist the hook and eye connection in electrically connecting the outer windings of adjacent units. The sleeve may be slit at one side as shown at 37 to provide sufficient resiliency to insure good electrical connection between the sleeve and end caps. The upper end of the sleeve is provided with an overhanging flange 38 which supports the sleeve on the lower end cap of the upper unit. While the units are being connected and disconnected, the sleeve is raised as shown in broken lines at the lower end of Fig. 2.

I claim:

1. In combination a non-inductive resistance element arranged for the application of a voltage wave to one end of said element, and for connection with means for recording the voltage wave produced at the other end of said element and means for shielding said resistance element from the effects of extraneous capacitance, said shielding means comprising a second non-inductive resistance element surrounding said first named element and connected in parallel relation with said first named element, the impedance of said respective elements being so balanced that adjacent points of said elements have substantially equal potentials during the time said circuits are subject to said voltage wave.

2. In a potentiometer a non-inductive resistance and a shunt resistance having a portion thereof surrounding said first named resistance to reduce the effect, on the voltage distribution along said first named resistance, of the capacitance between the portions of said first named resistance and ground.

3. A divider resistance made up of a plurality of units, each unit comprising a pair of non-inductive resistance elements disposed one within the other, and means for connecting said units in series, said means comprising contact members for electrically connecting the innermost elements of adjacent units together and the outermost elements of adjacent units together.

4. A divider resistance comprising a plurality of units arranged to be connected together in series, each unit comprising an inner core having a resistance element non-inductantly wound thereon, a tubular member surrounding said core and having a resistance element non-inductively wound thereon and extending along and surrounding the conductor on said core, and contact members at the ends of each of said units adapted to engage complementary contact members on adjacent units and to connect electrically the inner resistance elements and the outer resistance elements, respectively, of adjacent units.

5. A divider resistance comprising a plurality of units connected together in a string, each unit

- having inner and outer resistance elements, contact members at the ends of said units connected with the ends of said inner resistance elements, the contact members at adjacent ends of adjacent 5 units in a string being arranged to engage each other to connect said inner elements in series, fittings for mechanically connecting said units together in said string, the ends of the outer resistance elements in said units being connected 10 to said fittings respectively, so that the outer resistance elements of adjacent units in said string are electrically connected together by said 15 fittings.
6. Means for reproducing, at a lower voltage, the wave form of a high voltage impulse, said means comprising an elongated resistance member, said member being non-inductive so as to avoid distortion of the wave form by inductance,

and a second resistance member surrounding said first resistance member and connected in parallel relation therewith and having the resistance thereof distributed proportionately to said first named resistance so that equi-potential points in 5 said resistances will be in registration with one another, said second named resistance also being non-inductive so that the equi-potential registration of said resistances will not be disturbed by inductance for different wave forms of impressed voltage, said second resistance serving to shield said first resistance from the effect of extraneous capacitance so that the voltage at spaced 10 points on said first resistance will not be influenced by either inductance or capacitance and 15 will reproduce the wave form of the impressed voltage.
